DESIGN FOR A CHAIR LOUNGE

Joseph F. Laskowitz, St. Louis, Mo.

Application June 18, 1945, Serial No. 120,179

Term of patent 14 years

(Cl. D15—1)

To all whom it may concern:

Be it known that I, Joseph F. Laskowitz, a citizen of the United States of America, residing at the city of St. Louis, State of Missouri, have invented a new, original, and ornamental Design for a Chair Lounge, of which the following is a specification, reference being had to the accompanying drawing, forming a part thereof.

The appearance of the opposite side of the chair is the same as that shown.

I claim:

The ornamental design for a chair lounge, substantially as shown and described.

JOSEPH F. LASKOWITZ.
